UNITED STATES PATENT OFFICE.

FRED H. DOERR, OF GRAND RAPIDS, MICHIGAN, ASSIGNOR TO CHENEY TALKING MACHINE COMPANY, OF CHICAGO, ILLINOIS, A CORPORATION OF ILLINOIS.

NONSET STOP FOR TALKING MACHINES.

Application filed December 10, 1921. Serial No. 521,286.

To all whom it may concern:

Be it known that I, FRED H. DOERR, a citizen of the United States, residing at Grand Rapids, in the county of Kent and

5 State of Michigan, have invented certain new and useful Improvements in Nonset Stops for Talking Machines, of which the following is a specification.

This invention relates to a new and improved non-set stop for sound producing machines and more particularly to a device of this character adapted for use in connection with disk talking machines.

As is well known in the art, it is highly desirable to provide means for automatically stopping the rotation of the turn-table of such machines when the stylus and sound box reach the end of the record. In general, such records comprise a spiral groove, the groove being so modified as to produce the sound vibrations in the stylus and the groove ending at the end of the sound record. The stylus and consequently the tone arm are moved laterally by means of the coaction of 20 the stylus with the groove. At the end of the groove, the stylus ceases to advance but continues to trace a circular path upon the record if the latter continues to revolve. The rotation of the turn-table should be stopped 25 when the stylus reaches this point.

It is an object of the present invention to provide means cooperating with the turn-table and tone arm of a talking machine in such manner that the rotation of the turn-table is stopped when the tone arm ceases to move laterally relative to the turn-table.

It is an additional object to provide means of this character which stop the movement of the turn-table only when the tone-arm 40 is in certain predetermined portions of its range of movement.

It is a further object to provide a device of this character which is simple in design and construction and positive in operation.

45 Other and further objects will appear as the description proceeds.

Broadly, my invention comprises means associated with the turn-table and turn-table brake of a talking machine adapted to set the brake, the means being controlled by the location and movement of the tone arm. More particularly the device comprises 50 brake releasing means associated with the brake, this means being so connected with the tone arm that inward movement of the

tone arm tends to move the brake releasing means to inoperative position. Means are further provided for periodically returning the brake releasing means to operative position and the device also comprises moving 60 means, the path of movement of which intersects the operative position of the brake releasing means.

In the preferred form, this last-named moving means is provided with a control operated by the tone arm to vary its path of movement so that in certain positions of the tone arm, its path does not intersect the operative positions of the brake releasing means.

70 I have illustrated a preferred embodiment of my invention in the accompanying drawings, in which:

Figure 1 is a plan view of a phonograph showing my invention applied thereto, the 75 turn-table being partly broken away to more clearly show the working parts of the device, the parts being shown in the braking position;

Figure 2 is a fragmentary section taken 80 on line 2—2 of Figure 1;

Figure 3 is a plan view with the turn-table removed showing the parts in the non-braking position;

Figure 4 is a section taken on line 4—4 85 of Figure 1;

Figure 5 is a section taken on line 5—5 of Figure 1; and

Figure 6 is a fragmentary elevation showing the friction-connection element.

Referring now to the drawings, and in particular to Figure 1, the record 8 is supported upon the turn-table 9 and the latter is carried by the vertical spindle 10. The tone arm 11 is pivoted to the cabinet top 12 95 through the collar 13. The connecting lug 14 is rigidly secured to the tone arm 11 and rotates therewith. The operating link 15 is pivotally connected to the lug 14 at point 16 and has its opposite end pivotally connected, at 17 to the friction arm 18. This arm 18 is pivoted to stud 19 which latter is secured to the plate 20. The lever 21 is also pivoted upon the stud 19 and, as best shown in Figure 6, the arm 18 and lever 105 21 are maintained in frictional contact by the spring clip 22.

The outer reduced end 23 of the lever 21 fits through a slot 24 in the brake releasing lever 25. The lever 25 is pivotally 110

connected at 26 to the lever 25' which is pivoted to the bed plate 26' at point 27. The other end of the lever 25' fits between the bifurcated portion 28 of the brake latch 29. This latch is provided with the finger 30 adapted to engage the detent 31 carried by the brake lever 32. The brake lever 32 is connected to the lever 25' by means of a spring 33, and is provided with the operating handle 34 and the brake pad 35.

The guide link 36 is pivotally connected at 37 to the link 15 and is provided upon its opposite ends with a downwardly depending finger 38 fitting into a slot 39 in the plate 20. The link 36 is provided with a guide slot 40 having an offset portion 41, the purpose of which will be described hereafter.

The cross link 42 has a pin 43 traveling in the guide slot 40 of the guide link 36. The opposite end of the cross link 42 is pivotally connected at 44 to the push rod 45. The inner end of the push rod 45 is eccentrically connected at 46 to the rotating cam 47. This cam 47 is carried upon the upper end of a shaft, the lower portion of which is rigidly connected to the gear wheel 48. This gear wheel 48 is in mesh with the pinion 49 carried upon the turn-table spindle 10. The rock lever 50 is pivoted upon the stud 19, its inner end being adapted to engage the cam disk 47 to be thrust laterally about high point 51 on that disk. The opposite arm 52 of the rock lever has an upper set portion 53 adapted to engage the lever 21. The lever 25 fits within an upturned guideway 54 formed upon the plate 20. As best shown in Figure 3, the push rod 45 is provided with an angular face 55 which is adapted to engage the upturned end 56 of the lever 25, which action will be more fully described hereafter.

The tone arm 11 is provided, as shown, with a usual type of sound box 57, this being shown in Figure 3 as resting upon a member 58 located at one side of the turn-table.

In the operation of the device with the tone arm in the position shown in Figure 3, in order to start the turn-table the hand lever 34 is moved to the left to the position shown in Figure 3, this movement serving to release the brake. The brake mechanism itself is no part of the present invention and need not here be discussed in detail.

It will be obvious from an examination of Figure 3 where the brake is off and Figure 1 where the brake is on, that when the handle 34 is moved to the left, the spring 33 pulls upon the arm of the lever 25' to which it is attached, and this pull is transmitted to finger 30 of the lever 29 so that as soon as this finger clears the detent 31, it swings inwardly and engages the face of the detent. This swinging movement of the

lever 34 serves to move the brake pad 35 out of contact with the turn-table and the latter proceeds to revolve under the influence of the power applied by any suitable mechanism (not shown) through the turn-table spindle 10.

As the spindle 10 revolves, the pinion 49 causes the gear wheel 48 to revolve and the latter revolves the cam disk 47. Due to its eccentric connection to the cam disk 47, the push rod 45 reciprocates, being guided in its motion by the cross link 42. With the parts as shown in Figure 3, the cam surface 55 at the end of the push rod 45 will engage the end 56 of the lever 25 at the outward extreme of the reciprocation of the push rod. The thrust upon the lever 25 will move this lever and it will in turn rock the lever 25 about its pivot and this rocking motion transmitted to the lever 29 will move the finger 30 out of engagement with the detent 31 and the spring 33 will again swing the lever 32 about its pivot to bring the brake pad 35 into engagement with the turn-table.

However, if the tone arm 11 be swung inwardly after the turn-table is set in motion and the sound box be brought above the outer portion of the sound producing curve upon the record, this motion of the sound arm will be transmitted by the lug 14 to the link 15. The motion of the link 15 will serve to move the guide link 36 and the movement of this link is guided by its finger 38 which finger coacts with the guide slot 39 in the plate 20. When the tone arm has reached such a position that the needle is located above the outer portion of the record groove, the guide link 36 will have moved to such an extent that the guide stud 43, carried by the cross link 42, will be located in the offset portion 41 of the guide slot 40. This offset portion serves by means of the link 42 to swing the push rod laterally about its pivot. The link then so guides the reciprocatory movement of the push rod that the path no longer intersects the path of the lever 25.

Thus when the tone arm is within the range of movement which corresponds to the inter-relation of the offset portion 41 with the stud 43, the push rod 45 cannot operate the stop. In general, this range of movement of the tone arm will correspond to a distance extending from slightly outside the beginning of the record groove upon records of the largest dimension to a point somewhat outside that at which the record groove ceases upon the shortest records. Within this range, the non-set stop will be inoperative and this is highly desirable in order that the stop may not be unintentionally put into operation in the process of placing the stylus into engagement with the record groove.

When the tone arm is swung inwardly to

such an extent that the stylus reaches the end of the record groove, the stud 43 engages the upper straight portion of the guide groove 40 and the push rod 45 is again swung to the left so that its path of movement again intersects that of the lever 25. As the tone arm is swung inwardly, through the medium of the link 15, the friction arm 18 is rotated about the pivot 19 in the counterclockwise direction.

Through its frictional engagement with the lever 21, that lever is yieldingly rotated in the counterclockwise direction about the same pivot. The lever 25 is freely movable about its pivot 26 and as the lever 21 moves to the left, as seen in Figure 1, engagement of the ends 23 of this lever with slot 24 in lever 25, serves to swing the lever 25 to the left or in the clockwise direction about its pivot. This movement of the lever is limited by the stop 54. The movement is sufficient, however, to so carry the end 56 of the lever to the left as to take it out of the path of the push rod 45. Thus, with the lever 25 swung to the left, the push rod 45 cannot operate the lever to release the brake.

The high point 51 of the cam disk 47 engages the end of the lever 50 once in each revolution of the cam and swings that lever in the clockwise direction about its pivot. As this lever swings, the upwardly extending portion 53 upon its arm 52 engages the lever 21 and swings this last-named lever to the right, that is, in the clockwise direction and in the direction opposite to that which it is carried by its frictional engagement with the frictional arm 18. As the lever 21 swings to the right, it correspondingly swings the lever 25 to the right and again swings its end 56 into the path of movement of the push rod.

Thus as the tone arm gradually moves inwardly under the influence of the spiral groove, the lever 25 is periodically moved out of the path of the push rod by the frictional connection of the lever to the tone arm, and it is periodically moved back into the path of the push rod by the action of the cam. It will be apparent that if the frictional action ceases to operate upon the lever due to the tone arm ceasing to move laterally, the lever will remain in the path of the push rod and the latter will engage it and put on the brake. The brake will thus automatically be put on when the stylus reaches the end of the record groove.

It is to be understood that the high point 51 of the cam disk is so timed in regard to the reciprocatory movement of the push rod 45 that there will be ample time between the movement of the lever 25 into the operative position and the outward movement of the push rod for the frictional connection to again remove the lever from the path of the

push rod before the push rod reaches the outer position. This timing should be sufficient so that the turn-table may make more than one complete revolution. This is for the reason that many records are made in which the record groove is not concentric with the center of rotation of the record. Where such grooves are found, the tone arm although it progresses inwardly, has a back and forth movement under the influence of the eccentricity of the groove. Thus, if the stop operated in less period than one full revolution, it might be operated by the outward movement of the tone arm under the influence of the eccentricity. Where this operation extends one or more full revolutions, the eccentricity is compensated for in that the friction connection between the arm 18 and lever 21 serves to move the lever 21 in both directions with the tone arm.

It will be noted that when the brake is put on and the turn-table brought to a stop with the sound box at the inner end of the groove, the face 55 of the push rod will be in engagement with the end 56 of lever 25. As the tone arm is swung to the position in which it is shown in Figure 1, the push rod will be pulled to the right as the stud 43 passes through the offset portion 41 of the guide slot 40.

There is a certain amount of give in the lever 25 and its supporting parts and it will be thrust slightly longitudinally during this swinging movement by the push rod by the angular face 55 on the end of the push rod. As the push rod is again pushed to the left, when the stud 43 reaches the upper portion of the guide slot, the face 55 does not again slip in contact with the face 56 but the point of the face 55 engages the edge of the face 56 and thrusts the lever 25 to the left.

This is a desirable feature in that if the push rod were held positively in engagement with the lever 25, it would be impossible for the latch to engage and retain the brake in the unlocked position when again starting the turn-table. This is true since the finger 30 cannot swing to engage the detent 31 without the inter-engagement of the levers thrusting the lever 25 downwardly and the latter would be prevented by the push rod.

It should be noted, however, that if conditions were such that the push rod remained in engagement with the lever 25, the turn-table could be started by swinging the hand lever to the left and holding it in that position manually for a moment. As soon as the brake pad leaves the turn-table, the latter commences to revolve and the revolution of the cam disk carries the push rod away from the lever 25 and the brake is then latched in the off position by the force supplied through the spring 33. When thus latched, the hand lever may be released.

My device which has been fully described,

operates to automatically apply the brake to the turn-table when the tone arm ceases to travel inwardly at the end of the record groove. It also automatically stops the turn-table when the tone arm is swung outwardly and brought to the position of rest between operations of the machine. It is, however, so constructed that the brake cannot be unintentionally applied when the tone arm is moved through the range necessary for the application of the needle to the record groove in starting to play a record. The device is simple in design and positive in operation. It may be applied as shown under the record table without disfiguring the machine or causing any material modification in existing design or construction.

I am aware that many modifications of my construction may be made for the purpose of adapting it to varying uses and it is my intention to cover all such modifications coming within the spirit and scope of the appended claims.

I claim:

- 25 1. In combination with a rotating element and an element swinging relative to said rotating element, stopping mechanism adapted to stop said rotating element, operating means associated with said stopping mechanism, said means being so associated with the swinging element that movement of the latter in one direction tends to move the operating means to inoperative position, means periodically returning the operating means to operative position, and reciprocatory means, the path of movement of which intersects the operative position of the stopping mechanism operating means.
- 40 2. In combination with a rotating element and an element swinging relative to said rotating element, a brake for said rotating element, brake releasing means associated with the brake, said means being so associated with the swinging element that movement of the latter in one direction tends to move the brake releasing means to inoperative position, means periodically returning the brake releasing means to operative position, and reciprocatory means, the path of movement of which intersects the operative position of the brake releasing means.
- 55 3. In combination with a rotating element and an element swinging relative to said rotating element, a brake for said rotating element, brake releasing means associated with the brake, said means being so associated with the swinging element that movement of the latter in one direction tends to move the brake releasing means to inoperative position, means periodically returning the brake releasing means to operative position, moving means, the path of movement of which intersects the operative position of the brake releasing means, and
- 60 65 position of the brake releasing means, and

control means cooperating with the moving means to vary its path of movement.

4. In combination with a rotating element and an element swinging relative to said rotating element, a brake for said rotating element, brake releasing means associated with the brake, said means being so associated with the swinging element that movement of the latter in one direction tends to move the brake releasing means to inoperative position, means periodically returning the brake releasing means to operative position, moving means, the path of movement of which intersects the operative position of the brake releasing means, and control means cooperating with the moving means to vary its path of movement, said path being so varied that it fails to intersect the operative position of the brake releasing means when the swinging element is in a predetermined position.

5. In combination with a rotating element and an element swinging relative to said rotating element, a brake for said rotating element, brake releasing means associated with the brake, said means being so associated with the swinging element that movement of the latter in one direction tends to move the brake releasing means to inoperative position, means periodically returning the brake releasing means to operative position, moving means, the path of movement of which intersects the operative position of the brake releasing means, and control means cooperating with the moving means to vary its path of movement, said path being so varied that it fails to intersect the operative position of the brake releasing means when the swinging element is in a predetermined position.

6. In combination with a rotating element and an element swinging relative to said rotating element, a brake for said rotating element, brake releasing means associated with the brake, said means being so associated with the swinging element that movement of the latter in one direction tends to move the brake releasing means to inoperative position, means periodically returning the brake releasing means to operative position, moving means, the path of movement of which intersects the operative position of the brake releasing means, and control means operated by the swinging element cooperating with the moving means to vary its path of movement.

7. In combination with the turn-table and tone arm of a sound reproducing machine, a brake for said turn-table, brake releasing means associated with the brake, said means being so associated with the tone arm that inward movement of the latter tends to move the brake releasing means to inoperative position, means periodically returning

the brake releasing means to operative position, and a push rod, the path of movement of which intersects the operative position of the brake releasing means.

- 5 8. In combination with the turn-table and tone arm of a sound reproducing machine, a brake for said turn-table, brake releasing means associated with the brake, said means being so associated with the tone arm that 10 inward movement of the latter tends to move the brake releasing means to inoperative position, means periodically returning the brake releasing means to operative position, and a push rod having means giving it a 15 reciprocatory path of movement which intersects the operative position of the brake releasing means.

9. In combination with a turn-table and tone arm of a sound reproducing machine, 20 a brake for said turn-table, brake releasing means associated with the brake, said means being so associated with the tone arm that inward movement of the latter tends to move the brake releasing means to inoperative 25 position, means periodically returning the brake releasing means to operative position, and a push rod, the path of movement of which intersects the operative position of the brake releasing means, and a 30 link connected to the push rod to vary its path of movement.

10. In combination with the turn-table and tone arm of a sound reproducing machine, a brake for said turn-table, brake releasing means associated with the brake, said means being so associated with the tone arm that inward movement of the latter tends to move the brake releasing means to inoperative position, means periodically returning the brake releasing means to operative position, and a push rod, the path of movement of which intersects the operative position of the brake releasing means, and a link connected to the push rod to vary its path of movement, said path being so varied that it fails to intersect the operative position of the brake releasing means when the tone arm is in a predetermined position.

11. In combination with the turn-table and tone arm of a sound reproducing machine, a brake for said turn-table, brake releasing means associated with the brake, said means being so associated with the tone arm that inward movement of the latter tends 55 to move the brake releasing means to inoperative position, means periodically returning the brake releasing means to operative position, and a push rod, the path of movement of which intersects the operative position of the brake releasing means, and a link connected to the push rod to vary its path of movement, said path being so varied that it fails to intersect the operative position of the brake releasing means when 60 the tone arm is in a predetermined range of

positions intermediate its path of swinging movement.

12. In combination with the turn-table and tone arm of a sound reproducing machine, a brake for said turn-table, brake 70 releasing means associated with the brake, said means being so associated with the tone arm that inward movement of the latter tends to move the brake releasing means to inoperative position, means periodically returning the brake releasing means to operative position, and a push rod, the path of movement of which intersects the operative position of the brake releasing means, and a link operated by movement 75 of the tone arm and connected to the push rod to vary its path of movement.

13. In combination with the turn-table and tone arm of a sound reproducing machine, a brake for said turn-table, brake 80 releasing means comprising a swinging lever, a second swinging lever frictionally connected to the tone arm in such manner as to swing therewith, said second lever coacting with the brake releasing lever to 85 swing the latter, means periodically returning the brake releasing lever to operative position, and a push rod, the path of movement of which intersects a position of the brake releasing lever. 90

14. In combination with the turn-table and tone arm of a sound reproducing machine, a brake for said turn-table, brake releasing means comprising a swinging lever, a second swinging lever frictionally connected to the tone arm in such manner as to swing therewith, said second lever coacting with the brake releasing lever to swing the latter out of operative position, a rocking lever periodically returning the 100 brake releasing lever to operative position, and a push rod, the path of movement of which intersects the operative position of the brake releasing lever. 105

15. In combination with the turn-table and tone arm of a sound reproducing machine, a brake for said turn-table, brake releasing means comprising a swinging lever, a second swinging lever frictionally connected to the tone arm in such manner as to swing therewith, said second lever coacting with the brake releasing lever to swing the latter out of operative position, a rocking lever periodically returning the 110 brake releasing lever to operative position, and a push rod, the path of movement of which intersects the operative position of the brake releasing lever, and a link connected to the push rod and operated by the tone arm to 115 vary the path of movement that the push rod fails to intersect the path of movement of the brake releasing lever when the tone arm is placed adjacent the outer edge of the turn-table. 120

16. In combination with the turn-table 125

and tone arm of a sound reproducing machine, a brake for said turn-table, brake releasing means comprising a swinging lever, a second swinging lever frictionally connected to the tone arm in such manner as to swing therewith, said second lever coacting with the brake releasing lever to swing the latter out of operative position, a rocking lever periodically returning the brake releasing lever to operative position, and a push rod, the path of movement of which intersects the operative position of the brake releasing lever, and a link connected to the push rod and operated by the tone arm to so vary the path of movement that the push rod fails to intersect the path of movement of the brake releasing lever when the tone arm is placed adjacent the outer edge of the turn-table and intersects the path of movement when the tone arm is located outwardly of such position and inwardly of such position.

17. In combination with the turn-table and tone arm of a sound reproducing machine, a brake for said turn-table, brake releasing means comprising a swinging lever, a push rod, the path of movement of which intersects the path of movement of the brake releasing lever, said push rod being adapted to thrust the lever longitudinally to release the brake.

18. In combination with the turn-table and tone arm of a sound reproducing machine, a brake for said turn-table, brake releasing means comprising a swinging lever, a push rod, the path of movement of which intersects the path of movement of the brake releasing lever, said push rod being adapted to thrust the lever longitudinally to release the brake, and means connected to the push rod and operated by lateral movement of the tone arm adapted to move the push rod out of engagement with the release lever.

19. In combination with the turn-table and tone arm of a sound reproducing machine, a brake for said turn-table, brake releasing means comprising a swinging lever, a push rod, the path of movement of which intersects the path of movement of the brake releasing lever, said push rod being adapted to thrust the lever longitudinally to release the brake, and means connected to the push rod and operated by outward lateral movement of the tone arm adapted to move the push rod out of engagement with the release lever, subsequent inward movement of the tone arm serving to bring the push rod laterally against the release lever.

Signed at Grand Rapids, Michigan, this 3rd day of December, 1921.

FRED H. DOERR.
